UNITED STATES PATENT OFFICE.

PATRICK H. DALEY, OF LYNN, MASSACHUSETTS.

LEATHER-STAKING MACHINE.

SPECIFICATION forming part of Letters Patent No. 393,544, dated November 27, 1888.

Application filed June 11, 1888. Serial No. 276,719. (No model.)

To all whom it may concern:

Be it known that I, PATRICK H. DALEY, of Lynn, in the county of Essex and State of Massachusetts, have invented a new and useful Staking-Machine, of which the following is a specification, reference being had to the accompanying drawings, in which—

Figure 1 is a longitudinal central section of the machine embodying my invention, an auxiliary portion of the machine being shown in one position. Fig. 2 is a similar view showing the auxiliary attachment in another position. Fig. 3 is a plan, and Fig. 4 is a transverse section on line 4 4 of Fig. 1.

15 The object of my invention is to produce a machine specially adapted for stretching and softening hides and leather, in which danger of injuring the stock operated on is lessened, and by which the stock is more perfectly stretched and softened than in the machines hitherto used.

Another object of my invention is to produce a machine for this purpose which is simpler, and therefore cheaper, than the other machines of this kind now in use.

My invention consists, first, in the combination of a jaw provided with two projections with a jaw having a blade which, when the jaws are shut, extends between these projections, and, secondly, in combination with a reciprocating carrier provided with a fixed and also a fulcrumed jaw, of means for closing the jaws, as more fully described hereinafter.

In the drawings, which show my invention embodied in the best way now known to me, A is the main frame, B a carrier, and D D' the jaws.

Carrier B is mounted in ways *a* in frame A, and is provided with a jaw, D, fixed to it, and 40 a jaw, D', fulcrumed to it. Carrier B is reciprocated in ways *a*, preferably by the means shown—that is, by driving-wheel A', mounted in frame A, and a connecting-rod, *a'*, connecting the driving-wheel and the carrier in a way too 45 well known to require description. Jaws D D' are closed either by the engagement of a projection, F, (on a connecting-rod, *a'*,) with jaw D', or by the engagement of lever F' with a jaw, D', as desired. I prefer to construct my 50 machine with the projection F, (which is preferably a roll, as shown,) to engage the jaw D', which is recessed at F' to receive the roll in

such wise that when the connecting-rod *a'* is brought into the position shown in Fig. 2 the jaw D' is moved into its operative position 55 with jaw D, and also to provide the lever F', which is conveniently fulcrumed to frame A, and to make it of the proper form for co-operating with jaw D' by engaging, preferably, a roll, *f'*, on jaw D', and to control the lever by 60 a pedal, F''. In machines of this class heretofore constructed the mechanism for actuating the jaw has been more or less cumbersome and expensive, and the machines have made a great deal of noise in working, and this objection I 65 have eliminated in a great measure by the mechanism above explained.

In the course of my experiments relating to stretching hides, &c., I have discovered that it is of great practical importance that the 70 stock operated on should not be impinged at directly opposite points by a projection or roll and a blade. For example, as in many machines hitherto in use in which the stock when the jaws are closed has been held between a 75 roll or projection and the edge of the blade, the roll and the edge of the blade being directly opposed to each other, and the result being that tender skins and hides having soft spots when thus engaged are often torn during the 80 back-stroke of the jaws, I have also discovered that for the best results it is desirable that one of the jaws should be provided with two projections, which are preferably rubber rolls, and that the other jaw should be provided with 85 a blade or scraper, which, when the jaws are shut, is between the two projections referred to. In the drawings, *d d'* are the projections, and *d'* the blade or scraper, the two projections *d d'* being on one jaw, while the scraper is on the 90 companion jaw. This arrangement is an important feature of my invention, the roll *d'* acting on the stock after it has left the blade, and having a function as a polishing-roll, the skin or hide being nipped between the peripheral surface of the inner roll, *d*, and the inner surface of the blade *d'*.

The co-operation of the projections and the blade or scraper will be readily understood by all skilled in the art without further description. As skins and hides vary in thickness, it is highly desirable that the distance between the main projection *d* and the side of the blade *d'* which is nearest the projection should be

increased or diminished as desired, and this is readily accomplished by making one of the projections—say the projection d —adjustable, and for this purpose I form a slot, d^2 , in the 5 jaw which carries the projections or rollers, and secure one of the projections—say d —adjustably in the slot d^2 . The projection is readily secured in the slot d^2 by a clamping device, d^3 , and the combination of a pair of jaws, one 10 of which is provided with a scraper and the other of which is provided with two projections, one of which is adjustable, to increase or diminish the distance between it and the side of the blade, and between which the blade projects when the jaws are shut, is another feature of my invention.

What I claim is—

1. The combination of the reciprocating carrier B, provided with a fixed jaw, D, and a 20 jaw, D', with means, substantially such as described, for closing the jaws, the jaw D' being

fulcrumed in carrier B, all arranged and operating substantially as set forth.

2. The combination of jaws D D' and means 25 for reciprocating them, with projections d d^4 and blade d' , the projections being mounted in one jaw and the blade in the other jaw, and the blade extending between the projections when the jaws are closed, substantially as set forth.

3. The combination of the jaws D D' and 30 means for reciprocating them, with projections d d^4 and blade d' , the projections being mounted in one jaw and the blade in the other jaw, and one of the projections being adjustable, to increase or diminish the distance between it 35 and the side of the blade, substantially as and for the purpose set forth.

PATRICK H. DALEY.
